UNITED STATES PATENT OFFICE.

CHARLES S. THOMAS, OF SAN DIEGO, CALIFORNIA.

TOOL COUPLING.

Application filed June 12, 1922. Serial No. 567,620.

To all whom it may concern:

Be it known that I, CHARLES S. THOMAS, a citizen of the United States, residing at San Diego, in the county of San Diego and State of California, have invented a certain new and useful Tool Coupling, of which the following is a specification.

My invention relates to tools, more particularly to coupling means for tools and the objects of my invention are, first, to provide a tool coupling of this class which will securely hold the several parts of tools of various kinds and from which the removable parts may be easily removed; second, to provide a tool coupling of this class in which the various tool parts are held in absolute alinement with the tool receiving end of the tool holder; third, to provide a tool coupling of this class which will prevent the tool portion from getting out of the tool holder, getting loose or moving revolvably therewith; fourth, to provide a tool coupling means in which the sleeve securing the shank portions of the tool and tool holder can be made small enough so that it can readily follow an extension drill of a diameter reasonably larger than the normal shank thereof; fifth, to provide a novelly constructed coupling means for tools, and sixth, to provide a device of this class which is very simple and economical of construction, durable, efficient, easy to operate and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a side or plan view of a simple brace with my tool coupling means at the lower shank end thereof and with a drill held by the tool coupling means, with portions broken away to facilitate the illustration; Fig. 2 is a sectional view on an enlarged scale taken through 2-2 of Fig. 1; Fig. 3 is a fragmentary view of the brace or tool holder showing a slightly modified form of my tool coupling means; Fig. 4 is another slightly modified form of my tool coupling means shown secured to an ordi-

nary handle and having a screw driver member secured in said tool coupling means.

Like characters of reference refer to similar parts and portions throughout the several views of the drawings.

The tool holder 1, sleeve 2, and the tool member 3 constitute the principal parts and portions of my tool coupling in its preferred form.

The tool holder member 1 may be of any desired form, but preferably made for receiving and holding cutting and working tools. The normally lower shank portion 1^a of the brace, as shown in Fig. 1 of the drawings, which is generally provided with tool receiving means is provided at its end with a slightly reduced portion 1^b with a transverse hole 1^c provided in said reduced portion 1^b and connected with the end of the shank portion 1^a with a longitudinal outwardly diverging slot 1^d, forming an indenture in the end of said shank 1^a with an enlarged inner portion and resilient side portions so that the male portion 3^a of the tool member 3 can easily be inserted transversely in said indenture and be retained therein.

It will be here noted that the slot 1^d is preferably made slightly smaller than the portion of the shank 3^a conforming therewith and then sprung apart sufficiently to admit said shank making the outside diameter of the reduced portion 1^b of the shank 1^a slightly larger than its normal diameter to provide a friction lock for the sleeve 2.

A slot 1^e is also provided in the shank 1^a joining with the hole 1^c on the opposite side from the slot 1^d adapted to render the resilient side members more flexible. The shank portion 1^a of said tool holder 1 is also provided with threads 1^f, a portion of the distance from the reduced portion 1^b adapted to engage the internal threads on the externally knurled sleeve 2. Said sleeve is internally threaded the greater distance of its bore, the inside diameter of which is uniform throughout, so that it will serve as a solid sleeve over the joint portions of the various members. When it is desired to remove the tool member held by said tool holder, the sleeve 2 is screwed inwardly until the one end thereof passes beyond the transverse cylindrical portion of the joined members, as shown by dotted lines in Fig. 1 of the drawings, the member 3 may then be removed and another substituted.

In Fig. 3 of the drawings I have shown

a slightly modified form of my tool coupling means in which the shank portion 1^a is threaded at and near its ends instead of spaced therefrom as previously described. 5 The shank of the tool member 3 is preferably slightly smaller than the diameter of the shank portion 1^a and is removed from the tool holder by screwing the sleeve 2 in the opposite direction from that as shown 10 in Fig. 1 and slips over the shank of the tool member 3. It will be noted that the sleeve 2 is made considerably smaller than the one previously described and the shank 1^a of the tool holder 1 is more simple of 15 construction, making the latter device more economical to manufacture.

In Fig. 4 of the drawings I have shown another slightly modified form of construction from that shown in Fig. 1, in that a 20 reduced portion of the shank of the tool holder is on the opposite side from the threaded portion permitting the sleeve to butt up against the shoulder 1^f when securing the various tool members 3 in position in the socket of said tool holder.

Though I have shown and described a particular construction, combination and arrangement of parts and portions and certain modifications thereof I do not wish to 30 be limited to this particular construction, combination and arrangement nor to the modifications thereof, but desire to include in the scope of my invention the construction, combination and arrangement substantially as set forth in the appended claims. 35

Having thus described my invention what I claim as new and desire to secure by Letters Patent is:

1. A tool coupling, including a shank member provided with a transverse hole therethrough and with reduced and outwardly diminishing furcations with fin ends, a tool member having a transverse head and a reduced outwardly increasing, angled male end conforming in shape but slightly larger than the opening formed by the furcations, said head fitting tightly the hole and said angled end adapted to spread the furcations of said shank member making it larger, and a sleeve adapted to fit over said shank member and be shifted thereon toward the tool member for clamping said tool member between the furcations of said shank. 40 45 50

2. A tool coupling, including a shank member provided with a circular transverse hole therethrough and with reduced and outwardly diminishing furcations with fin ends, a tool member having a circular transverse head and a reduced, outwardly increasing, angled male end conforming in shape but slightly larger than the opening formed by the furcations, said head fitting tightly the circular hole and said angled end adapted to spread the furcations of said shank member making its end larger, and an internally threaded sleeve adapted to fit over said shank member and be shifted thereon toward the tool member for clamping said tool member between the furcations of said shank. 55 60 65 70

In testimony whereof, I have hereunto set my hand at San Diego, California, this 7th day of June, 1922.

CHARLES S. THOMAS.
